GUSTAVE LIDSEEN, OF CHICAGO, ILLINOIS.

LEVER OPERATING MECHANISM FOR OIL-CANS.

1,345,788.

Specification of Letters Patent. Patented July 6, 1920.

Application filed March 19, 1917. Serial No. 155,716.

To all whom it may concern:

Be it known that I, GUSTAVE LIDSEEN, a citizen of the United States, and a resident of the city of Chicago, in the county of Cook 5 and State of Illinois, have invented certain new and useful Improvements in Lever Operating Mechanism for Oil-Cans; and I do hereby declare that the following is a full, clear, and exact description of the same, 10 reference being had to the accompanying drawings, and to the numerals of reference marked thereon, which form a part of this specification.

This invention relates to an improved 15 form of an oil can wherein a lever operated oil ejecting mechanism is mounted within the cap of the oil can to force oil out of the oil can spout under direct pressure by actuation of the lever, said forcing out of the oil being 20 accomplished independently of any operation of the oil can base.

It is an object of this invention to construct an oil can having an ejecting mechanism in the cap thereof for forcing oil from 25 the spout of the can under pressure.

It is also an object of this invention to provide an improved oil can adapted to force oil from the spout of the can independently of any operation of the can bottom.

30 It is a further object of this invention to construct an oil can wherein a spring controlled ejecting mechanism is mounted within the lower end of the spout of the can for entrapping oil within the spout and forcing it therefrom under pressure.

It is an important object of this invention to provide an oil can having a removable spout cap thereon, wherein an ejecting mechanism is mounted independently of the can 40 for forcing oil from the can under pressure.

It is furthermore an object of this invention to construct an oil can wherein an exteriorly operable lever controlled ejecting mechanism is disposed within the cap 45 and nozzle of the oil can for forcing oil therefrom.

It is an important object of this invention to provide an oil can simple and effective in construction, having an exteriorly operable 50 ejecting mechanism therein for forcing oil from the can, said ejecting mechanism being removable with the spout of the can to permit filling of the can with oil.

Other and further important objects of 55 this invention will be apparent from the disclosures in the drawings and specification.

The invention (in a preferred form) is illustrated in the drawings and hereinafter more fully described.

On the drawings:

Figure 1 is a side elevational view of an oil can embodying the principles of my invention.

Fig. 2 is a top plan view thereof.

Fig. 3 is an enlarged section taken on line 3—3, of Fig. 2, with parts broken away.

Fig. 4 is an enlarged fragmentary section taken on line 4—4 of Fig. 3, with parts omitted.

Fig. 5 is an enlarged detail section taken on line 5—5, of Fig. 3, with parts omitted.

Fig. 6 is a bottom plan view of the oil can top removed from the can.

Fig. 7 is a fragmentary top plan view of the oil can with the cap removed.

Fig. 8 is an enlarged detail section, taken on line 8—8, of Fig. 2, with parts omitted.

Fig. 9 is a view similar to Fig. 5, of a modified form of a pump operating mechanism, with parts shown in elevation.

Fig. 10 is a section taken on line 10—10, of Fig. 9, with parts shown in elevation.

Fig. 11 is a side elevational view of an oil can showing a modified form of lever operating means.

As shown on the drawings:

The oil can comprises a can, body portion or container 1, having a bottom or base piece of any desired form rigidly secured thereto, by brazing or other means, to afford an air tight joint. The upper end of the can 1, is rounded or tapered inwardly to connect with an integral neck or collar 2, the upper margin of which is bent outwardly 95 at right angles to afford a flange 3, having integrally formed on opposite sides thereof, by cutting away portions of the flange, curved or arc shaped ears, lugs or quadrants 4, one end of each of which is in the plane 100 of the flange 3, while the other end as denoted by the numeral 5, is deflected downwardly, said ears 4, being disposed with the like ends thereof positioned diametrically opposite one another as clearly shown in 105 Fig. 7.

Removably engaged upon the can is a cylindrical casing or cap 6, having integrally formed or rigidly secured on the upper end thereof by soldering or other 110 suitable means, a centrally passaged outwardly tapering spout or nozzle 7. Inte-

- grally formed at right angles to the lower end of the cap 6, is a circular cover plate 8, the margin of which is bent downwardly at right angles and then inwardly to afford 5 an inner peripheral groove, and an integral flange 9, of which oppositely disposed portions have been cut away to form oppositely disposed ears, lugs or quadrants 10, one end of each of which lies in the plane 10 of the flange 9, while the other end of each thereof is bent outwardly or deflected as denoted by the numeral 11, said ends of the ears 10, are arranged with the similar ends thereof disposed diametrically opposite one 15 another as shown in Fig. 6. Removably seated within the inner peripheral groove of the cover plate 8, is a washer or packing ring 12, made of rubber or any other suitable material.
- 20 Mounted within the cylindrical cap 6, is an oil ejecting mechanism comprising a cylindrical plunger 13, having disposed a short distance therebelow a disk, plate or head 14, integrally connected or rigidly attached to the plunger 13, by means of oppositely disposed straps or arms 15, thus providing outlet openings 16, between the plunger 13, and the plate 14. Positioned within the plunger 13, and the cap 6, with 25 its lower end seated upon the upper surface of the plate 14, is a spiral spring 17, the upper end of which presses against the inner surface of a shoulder 18, formed at the upper end of the cap 6, for the purpose.
- 30 To hold the ejecting mechanism parts in position the plate 14, has formed on its lower surface two parallel ribs 19, one disposed on each side of the center of the plate, to afford a seat for an actuating and sup-
- 35 porting arm 20, the inner end of which is free to slide between said ribs and press upwardly against said plate 14, while the outer end thereof is curved upwardly and projects through a slot 21, provided in a
- 40 socket 22, integrally formed by depressing a portion of the cover plate 8, at one side of the cap 6, said outer end of the arm 20, being rigidly secured, by brazing or other means, to a cup or curved member 23, mov-
- 45 ably seated within the socket 22 to form a non-leaking joint. To hold the cup 23, seated within the socket 22, against the action of the spring 17, a small spiral spring 24 is seated within the cup 23, and held compressed by means of an arched strap 25, the ends of which are rigidly secured to the cover plate 8, by rivets or other suitable means, with the arched portion thereof bearing upon the upper end of the
- 50 spring 24. The springs 17 and 24, are compressed an amount sufficient to permit the force of the spring 17, in the normal position of the force pump as shown in Fig. 3, to hold the plunger plate 14, positioned be-
- 55 low the cover plate 8, with the openings 16,

affording an outlet for oil from the can 1, into the cap 6, when the oil can is turned to one side or inverted. To operate the ejecting mechanism of the oil can from the exterior of the device a lever or finger piece 70 26, has its inner end integrally connected or rigidly secured to the outer side of the cup 23, while the outer end thereof is curved to extend to a convenient position on one side of the oil can.

75 In the modified form of the invention disclosed in Figs. 9 and 10, the construction of the oil can is identical with that described and shown in Figs. 1 to 8, of the drawings, with the exception that a semi-cylindrical socket 27, is integrally formed in the cover plate 8, said socket 27, having a transverse slot 28, therein, through which projects an actuating lever or arm 29, the inner end of which is adapted to slidably 80 seat below the plunger plate of the device. Rotatably seated within the socket 27, is a hollow cylinder 30, held in position to afford a non-leaking joint by means of an arched strap 31, the ends of which are rigidly secured upon the cover plate 8, said cylinder 85 having apertures therein to permit the lever 29, which is suitably bent, to project through one of the cylinder apertures registering with the slot 28, and out through the other aperture, thus affording a means for 90 rotating the cylinder 30, by depressing the outer end of the lever 29, and thereby raising the inner end of the lever to actuate the 95 ejecting mechanism of the oil can. 100

The modified form of oil can shown in Fig. 11, is practically identical in construction with the form of the device disclosed in Fig. 1, except that the lever 26 is replaced by a lever 32, having pivotally attached to the outer end thereof, by means of a friction knuckle 33, or other suitable joint, a hooked hanger or actuating arm 34, to afford a suitable and convenient means for 105 operating the force pump of the oil can. 110

The operation is as follows:

When it is desired to use the oil can the top is removed and oil is placed within the can 1, through the open collar 2. To replace the oil can top which comprises the 115 cover plate 8, the cap 6, spout 7, and the ejecting mechanism, the cover plate 8, is placed with its flange 9, resting upon the can flange 3, and with the cover plate ears 10, registering with the cut out portions 120 of the flange 3. The deflected ear portions 11, are disposed adjacent the raised portions of the ears 4, in which position the cover plate 8, is given a quarter turn in a clockwise direction to permit the ears 10, to 125 slidably engage below the ears 4, to frictionally hold the top in position upon the can 1, with the packing 12, pressing upon the flange 3, to afford an air tight fit and thus eliminate leakage.

To use the oil can the same is turned to one side or inverted with the mouth of the spout 7, engaged in or upon the device requiring lubrication, in which position the oil in the can flows through the openings 16, into the cap 6. The lever 26, is now depressed, rotating the cup 23, in the socket 22, and thereby moving the arm 20, in the slot 21, simultaneously raising the inner end 10 of said arm and sliding the same between the ribs 19, thus compressing the spring 17, and forcing the plunger plate 14, into the cylindrical cap 6, entrapping the oil therein and forcing the same out of the mouth of the spout 7, under pressure independently of any flexing of the sides or of the bottom of the oil can.

In the modified form of pump actuating mechanism shown in Figs. 9 and 10, to operate the ejecting mechanism of the oil can, the outer end of the lever 29, is depressed, thereby rotating the cylinder 30, in the socket 27, and moving the central portion of the lever 29, in the slot 28, to simultaneously elevate and slide the inner end of the lever on the lower surface of the plunger plate, thus forcing the same into the oil can cap under pressure to force entrapped oil out of the mouth of the spout, 30 when the oil can is tipped to one side or inverted.

I am aware that various details of construction may be varied through a wide range without departing from the principles of this invention, and I therefore do not purpose limiting the patent granted otherwise than necessitated by the prior art.

I claim as my invention:

1. In a device of the class described a 40 plate, a socket formed thereon having a slot

therein, a lever projecting through said slot, means on said lever adjustably seated in said socket to afford a fulcrum for the lever, and retaining means on said plate for adjustably holding said means in place.

45

2. In a device of the class described a socket having a slot therein, a curved member adjustably disposed to seat in said socket, a lever connected with said curved member and projecting through said slot, 50 and means for holding said curved member adjustably seated in said socket to form a non-leaking joint.

3. In a device of the class described a socket having a slot therein, a lever projecting through said slot, means on said lever adjustably seated in said socket to afford a fulcrum for the lever, retaining means for holding the means on said lever adjustably seated in said sockets, and a 55 mechanism connected with said lever adapted to be operated thereby.

4. In a device of the class described a socket member having a slot therein, a lever projecting through said slot, a curved member in said socket member affording a fulcrum for said lever, means adapted to be operated by said lever, a spring engaged in said curved member to hold the same in position to form a non-leaking joint with 65 70 said socket member, and means for holding said spring in place.

In testimony whereof I have hereunto subscribed my name in the presence of two subscribing witnesses.

GUSTAVE LIDSEEN.
